UNITED STATES PATENT OFFICE.

JAMES F. McELROY, OF ALBANY, NEW YORK.

DESIGN FOR AN ELECTRIC-HEATER CASE.

SPECIFICATION forming part of Design No. 24,292, dated May 7, 1895.

Application filed March 7, 1895. Serial No. 540,896. Term of patent 14 years.

To all whom it may concern:

Be it known that I, JAMES F. McELROY, a citizen of the United States, residing at the city and county of Albany, State of New York, have invented and produced a new and original Design for an Electric-Heater Case, of which the following is a specification, reference being had to the accompanying drawing, forming a part thereof, in which my heater is shown in perspective.

My electric heater case has a cylindrically formed body with a lower flanging shaped base ring supported by suitable legs, surmounted by an overlapping flanging cover, with a cap and urn.

The leading feature of my design consists in the heater case of the shape shown pro-

vided with a series of openings A along the upper edge of the flanging collar B on the drum D. Upon the flanging collar B there rests an overlapping cover C, which is provided with an ornamented cap E and urn F. The heater case is supported by means of suitable legs G G leaving an open space between the floor and the lower end of the drum D.

25

What I claim as my invention, and desire to secure by Letters Patent, is—

The design for an electric heater case as herein shown and described.

JAMES F. McELROY.
